UNITED STATES PATENT OFFICE

ROGER J. DEVER, OF WILKES-BARRE, PENNSYLVANIA

HUMIDIFIER

Application filed September 12, 1928. Serial No. 305,575.

This invention has reference primarily to a humidifier, medicator and deodorizer, but it is to be understood that the device may be adapted for many other uses wherein vapors 5 are carried into the air.

An important object of the invention is to provide a device of this character wherein the heat is supplied electrically, thereby eliminating obnoxious fumes being carried into 10 the air which is being treated by the device.

A further object of the invention is the provision of means to support the wick of the device in an elevated position and in such a manner that the moisture with which the 15 wick is saturated cannot find its way into the heating chamber to short circuit the electric energy passing into the heater of the device.

With the foregoing and other objects in view which will appear as the description 20 proceeds, the invention resides in the combination and arrangement of parts and in the details of construction hereinafter described and claimed, it being understood that changes in the precise embodiment of the invention 25 herein disclosed, may be made within the scope of what is claimed, without departing from the spirit of the invention.

Referring to the drawings:

Figure 1 is a perspective view of a device 30 constructed in accordance with the invention.

Figure 2 is a vertical sectional view through the device.

Figure 3 is a plan view thereof.

Figure 4 is a bottom plan view of the wick 35 supporting frame.

Referring to the drawings in detail, the device includes a base 5 that provides a support for the lamp socket 6 that is secured to the flanges 7 of the base.

Forming a part of the base is an upstanding 40 curved flange 8 formed with threaded openings to accommodate the screws 9 that secure the liquid container to the base. This liquid container is formed of an outer section 10 and an inner section 11, the sections 10 and 45 11 being spaced apart to provide a water compartment in which the water or liquid under treatment may be placed.

The inner and outer sections 10 and 11 of 50 the liquid container are secured together at

their bases, by means of an expandable cement 12 which insures a fluid tight connection between the inner and outer sections, but at the same time permits of expansion and contraction of the container at its point of contact with the supporting base, without danger of breaking the seal. To further insure against breakage by expansion under the heat of the heating element, an elastic ring 13 is positioned on the lower curved end of the 60 outer section of the container for contact with the screws 9.

Positioned on the inner section of the container is a wick supporting frame including the supporting ring 14 which is in the form 65 of a band stamped in such a way that tongues 15 are provided, the tongues extending inwardly to provide a support for the supporting frame.

The wick supporting frame is substantially 70 dome-shaped and embodies curved members 16 formed of sheet metal having their ends secured to the ring 14, the members 16 crossing each other at points directly over the upper end of the electric lamp 17 which is 75 positioned in the lamp socket, and which supplies the heat for heating the wick and causing a vapor to arise therefrom.

In order that the heat from the lamp 17 may pass upwardly, openings 18 are provided, 80 which openings may be formed by stamping the sheet metal of which the members 16 are constructed. From the foregoing it will be obvious that the wick supporting frame is of such a construction that it will extend beyond 85 the outer surface of the inner section of the liquid container and direct any liquid which may collect thereon, downwardly along the outer surface of the inner section.

Forming an important part of the invention 90 is a cover or wick 19 which is constructed in such a way that it will closely fit over the wick supporting frame in dome-like formation, the lower edge of the wick extending to a point adjacent to the bottom of the liquid 95 container which in operation is filled with the liquid to be used with the device.

In order that the wick and liquid contained in the device will be guarded against germs 100 and other foreign matter, a removable cover

20 is provided and is so constructed that it may be readily and easily positioned or removed.

In the use of the device the liquid container 5 is filled with liquid and the cover 20 removed. The electric current for lighting the lamp 17 is turned on and the heat from the lamp will heat the wick which is saturated with the liquid placed in the liquid container.

10 When the temperature reaches a certain degree, it is obvious that vapors will be thrown off from the wick, which vapors humidify the air and if the liquid is treated with medicine, it is obvious that the air will be medicated.

15 While I have shown and described the device for use as a humidifier, medicator, or deodorizer, it is to be understood that the device is adapted for many other uses of a similar character without departing from the 20 spirit of the invention.

I claim:

1. A humidifier including a base, a body portion mounted on the base and including an inner tubular member having an open 25 upper end, a frame positioned over the open upper end of the inner tubular member, said frame embodying a ring member, laterally extended members formed on the ring member and resting on the upper end of the inner 30 tubular member to support the frame, curved members having their ends connected with the ring member defining a dome, a wick positioned over the frame and adapted to absorb liquid contained in the body portion, and 35 means for directing heat to the interior of the inner tubular member to vaporize liquid on the wick.

2. A humidifier including a base, a body portion supported by the base and including 40 an inner tubular member having an open upper end, a wick supporting frame mounted on the upper end of the inner tubular member, said frame including a ring member surrounding the upper end of the inner tubular 45 member, a wick positioned over the frame to close the open end of the inner tubular member, portions of the wick extending downwardly over the ring member and in spaced relation with the inner tubular member, said 50 wick adapted to absorb liquid contained in the body portion, and means for directing heat to the wick to vaporize liquid on the wick.

3. A humidifier including a base, a body portion mounted on the base, said body portion including an inner tubular member having an open upper end, a frame positioned on the inner tubular member and including a supporting ring, curved members formed of lengths of sheet metal, forming a part of the 60 frame and having connection with the ring, said curved members having openings formed therein to permit heat to pass therethrough, a wick positioned on the frame for closing the open end of the inner tubular member, said wick adapted to absorb liquid

in the body portion, and means for directing heat to the wick to vaporize the liquid thereon.

In testimony that I claim the foregoing as my own, I have hereto affixed my signature. 70
ROGER J. DEVER.
